(57) **CLAIM**

The ornamental design for a remote patient monitoring system with incorporated tablet, as shown and described.

DESCRIPTION

FIG. 1 is a perspective view of a remote patient monitoring system with incorporated tablet showing my new design.

FIG. 2 is a front view of a remote patient monitoring system with incorporated tablet showing a new design.

FIG. 3 is a back view of a remote patient monitoring system with incorporated tablet showing my new design.

FIG. 4 is a right side view of a remote patient monitoring system with incorporated tablet showing my new design.

FIG. 5 is a left side view of a remote patient monitoring system with incorporated tablet showing my new design.

FIG. 6 is a top view of a remote patient monitoring system with incorporated tablet showing my new design; and,
FIG. 7 is a bottom view of a remote patient monitoring system with incorporated tablet showing my new design.

The broken lines are included for the purpose of illustrating portions of the remote patient monitoring system with incorporated tablet that form no part of the claimed design.

1 Claim, 4 Drawing Sheets
